UNITED STATES PATENT OFFICE.

BENJAMIN BILLINGS, OF MACEDON, NEW YORK.

IMPROVED WATER-WHEEL.

Specification forming part of Letters Patent No. **24,608**, dated July 5, 1859.

To all whom it may concern:

Be it known that I, BENJAMIN BILLINGS, of Macedon, in the county of Wayne and State of New York, have invented a new and Improved Conical Combined Action Water-Wheel; and I do hereby declare that the following is a full and exact description thereof, reference being had to the accompanying drawings, making part of this specification—

Figure 1 being a central vertical section of the water-wheel and all its immediate appendants in place; Fig. 2, a plan of the wheel proper, a portion of the top being broken away to show its interior construction; Fig. 3, a horizontal section in the plane indicated by the line xx , Fig. 1, exhibiting a plan of the crown, a portion of the top thereof being broken away to show the interior construction.

Like letters designate corresponding parts in all the figures.

My invention consists in an improved construction and arrangement of the turbine, by which an increased combined direct and centrifugal action and reaction are produced, and consequently a larger per cent. of power is obtained from the force of a given quantity and head of water.

The improved construction consists in making the crown A and wheel B conical in such a manner that the sluices or guide-curves $g g$ of the one and the channels $h h$ of the other shall have an inclination downward and outward, the channels being in continuation of the sluices, as represented. This inclination should best be at an angle of about forty-five degrees with the horizontal plane, so that the beneficial results of giving as direct a motion to the water from the cistern or forebay C entirely through the wheel as possible, and a direction thereof when it leaves the wheel as nearly horizontal as possible may be attained at the same time, thereby securing the maximum advantage of both results consistent with each other.

The crown A in construction has a cylindrical flange c projecting upward, to which the cylindrical forebay C is secured, as represented in Fig. 1. It has also a conical flange d projecting outward over and a little above the wheel B to receive suitable legs or supports $a a$.

The hub i of the wheel B is secured fast

and tight to the spindle E, which runs in a suitable step G at the bottom and in a stuffing-box m in the cover of the forebay.

The joints between the crown and wheel are at $t t$, where the upper and lower plates thereof come together, those of the wheel being in exact continuation of those of the crown, as seen in Fig. 1. The lower plate of the crown fits into a groove or recess in the bottom or lower plate of the wheel, and the upper plate of the wheel in like manner fits into a groove or recess in the top or upper plate of the crown. These joints are close, and the upper joint is the only one through which any waste of water can take place, and that way not being so direct as the channels of the wheel, even if it were not close, no appreciable amount of water could escape thereby. In truth, the conical form of the crown and wheel enabling one to cover the other, as a cap, almost completely obviates any waste of water.

The sluices $f f$ of the crown are curved in a spiral direction according to mathematical rules familiar to those skilled in the art of constructing this class of water-wheels, and the channels of the wheel are correspondingly curved in the opposite direction in like manner according to certain fixed rules. The direction of the sluices of the crown where they meet the channels of the wheel should be nearly at right angles to said channels, so as to give the fullest effect to the direct action of the water as it impinges on the diaphragms or buckets which separate the said channels; also, the direction of the channels at their orifices is so nearly tangential to the periphery of the wheel as to attain the greatest practicable force of reaction. The conical form of the crown and wheel, by giving the water the directest course practicable and consequently by giving it the greatest possible velocity in its passage through them, also increases the centrifugal force of the wheel. Thus all the available forces of the water-wheel are enhanced to the greatest practicable degree.

The sluice-gate D is of cylindrical form and fits closely into a central space in the crown A of the same shape, whence the sluices $g g$ open all around. The lower edge s of this sluice-cylinder makes a tight joint at r on the

bottom plate of the crown when the cylinder is closed completely down, and a shoulder or rim p is formed on the upper end of the cylinder, so as to shut down and make a tight joint upon the upper edge f of the upper plate of the crown. Thus when the sluice-cylinder is shut down it closes the crown water-tight. The sluice-cylinder is controlled by means of rods n n , extending up out of the forebay and connected with any suitable contrivance for the purpose.

What I claim as my invention, and desire to secure by Letters Patent, is—

The conical crown A and conical wheel B, constructed and combined substantially in the manner and for the purposes herein specified.

BENJAMIN BILLINGS.
